MAGNETRON

Irving Wolff, Merchantville, N. J., assignor to
Radio Corporation of America, a corporation
of Delaware

Application July 27, 1939, Serial No. 286,749

7 Claims. (Cl. 250—27.5)

This invention relates to magnetrons and particularly to magnetrons having means adapted to reduce the velocity of electrons impinging on the collecting electrodes to thereby increase the efficiency of the device.

The principal object of this invention is to increase the efficiency of a magnetron oscillator, detector, or amplifier by reducing the velocity of electrons which impinge on the end plate or other collecting electrodes so that the energy loss represented by the heating of the collecting electrodes is greatly reduced. Further objects of this invention include the provision of an improved electrode structure for thermionic discharge tubes of the magnetron type, and the provision of one or more auxiliary grid electrodes which are located adjacent the collecting electrode.

This invention will be better understood from the following description when considered in connection with the accompanying drawing. Its scope is indicated by the appended claims.

Figure 1 of the drawing represents the application of this invention to a conventional magnetron; and Figure 2 represents the application of this invention to a magnetron of the "electron beam" type.

Referring to Fig. 1 of the drawing, a filamentary cathode 1 is mounted within an evacuated envelope 3 in the usual manner. Surrounding the cathode is a segmented cylindrical oscillatory anode electrode comprising two semicylindrical sections 5 and 7 which are connected, respectively, to the two conductors 9 and 11 of a resonant Lecher wire system, which terminates in an antenna 13. A positive potential is supplied from a battery 15, or the like, which is connected between both oscillatory electrode segments and the cathode.

A pair of end plate collecting electrodes 17 and 19 are mounted adjacent the opposite ends of the anode structure, and are perpendicular to the axis of the cathode. End plate electrodes, as such, are well known in the art. They consist of small metallic discs which are connected to a source of positive potential. Their purpose is to draw electrons from the anode-cathode region to prevent the building up of a space charge near the cathode. They are mounted within the envelope in any convenient manner, as is well known.

An axial magnetic field is produced by means of a magnet, the pole pieces of which are indicated at S and N. I have found that the efficiency of operation of a conventional magnetron oscillator having oscillatory and end plate collecting elec-

trodes is greatly reduced by the energy which is absorbed in the end plate collecting electrodes. The collecting electrodes are at a high positive potential so that electrons released from the cathode are given an axial velocity which is of such a magnitude that the electrodes frequently become extremely hot.

For stable operation I have found that the voltage applied to the end plates may be sufficient to produce an end plate direct current which is as much as fifty times the direct oscillatory electrode current. Thus the major part of the power dissipation in such a magnetron is in the end plates. Since oscillations are produced between the two segments of the cylindrical electrode it is called the oscillatory electrode, while the end plate electrodes are also known as collecting electrodes.

In accordance with the present invention, a pair of rectilinear accelerating electrodes 21 and 23 are located between each end plate collecting electrode and the respective adjacent end of the anode structure. A high positive potential with respect to the cathode is applied to the accelerating electrodes 21, 23, by means of a suitable tap on the battery 15. The end plate electrodes, however, are placed at a lower positive potential with respect to the cathode, by means of a separate battery or a connection to battery 15, or the like. The amplitude of the positive potential on the accelerating electrodes is adjusted so that the desired axial velocity is given to electrons which are released from the cathode, but due to the grid-like structure of the accelerating electrodes, most of the electrons pass through the accelerating electrodes at a high velocity and come within the influence of the less positive end plate collecting electrodes 17 and 19. As a result, their velocity is greatly reduced so that when they impinge on the end plate electrodes, they contain little or no energy.

When accelerating grids are used the end plate collecting electrodes function as decelerating electrodes. The amplitude of the potential which is applied to the decelerating end plate electrodes must be made high enough so that the desired electron flow can be obtained, taking into account space charge effects in the space between the accelerating and the decelerating electrodes. The decelerating electrode is designed to minimize these effects. The potential of the accelerating electrode is adjusted to control the space charge inside the oscillatory electrode.

The grid-like accelerating electrodes 21 and 23 are formed of a number of parallel wires, or may

consist of a grid-like mesh, or may take the form of any of the well known grid electrodes which are common in the prior art.

While I have illustrated a magnetron utilizing a pair of semicylindrical anode electrodes, it is to be understood that this invention is not limited to the particular arrangement shown. For example, Fig. 2 illustrates the application of this invention to a magnetron of the "electron beam" type, a description of which is found commencing at page 14 of a book entitled "Magnetron-Oscillations of Ultra-short Wavelengths and Electron-Oscillations in General" by Kinjiro Okabe, published in Japan by Shokando.

The structural arrangement of an electron beam magnetron comprises a cylindrical electrode 25 at one end of which a cathode 27 is mounted. Facing the open end of cylinder 25 opposite the cathode are two semicircular anode or oscillatory electrodes 29 and 31, to which a resonant Lecher wire system 33 and an antenna 35 are connected. An axial magnetic field is provided by a field winding 39. The previously known arrangements, however, do not include the spiral grid 37 which is mounted within the cylindrical electrode 25.

Neglecting for a moment the function of the grid, the operation of the tube is believed to be as follows: Electrons released from the cathode 27 are directed radially outwards by the positive potential of cylinder 25, which then functions as an accelerating electrode. The magnetic field, however, causes the electrons to rotate about the axis of the cylinder, while the positive potential applied to the anode electrodes 29, 31 causes them to move axially away from the cathode. By properly relating the resonant period of the oscillatory circuit 33 with the period of revolution, oscillations are sustained in the oscillatory system 33.

In accordance with this invention a grid accelerating electrode 37 is placed between the cathode 27 and the collecting electrode 25. The cylindrical electrode 25 then becomes the decelerating electrode and the grid 37 is the accelerating electrode. The purpose and operation of the grid is the same as in the previous illustration, and need not be explained again in detail.

I claim as my invention:

1. An electron discharge device comprising cathode and anode electrodes mounted within an evacuated envelope, a pair of accelerating electrodes respectively positioned adjacent the opposite ends of said anode electrode, and a pair of decelerating end plate electrodes adjacent said accelerating electrodes.

2. A magnetron comprising a linear cathode, a cylindrical electrode mounted about said cathode,

a pair of reticular accelerating electrodes respectively positioned adjacent the opposite ends of said cylindrical electrode and perpendicular to said cathode electrode, and a pair of decelerating end plate electrodes, said accelerating electrodes being positioned between said cylindrical and said decelerating end plate electrodes.

3. An electron discharge device comprising a cathode, a cylindrical electrode positioned about said cathode, a pair of accelerating electrodes respectively positioned adjacent the opposite ends of said cylindrical electrode, and a pair of decelerating end plate electrodes external to said accelerating electrodes, said accelerating electrodes comprising a grid-like mesh positioned between said cylindrical and said decelerating electrodes and adapted to attract electrons liberated by said cathode.

4. The combination including an electron emitting cathode, an oscillatory electrode positioned about said cathode, means for causing electrons emitted from said cathode to follow spiral paths about said cathode, accelerating electrodes positioned opposite the open ends of said oscillatory electrode for causing portions of said electrons to move in axial directions parallel to said cathode, and electrode means for establishing a decelerating potential gradient for reducing the axial velocity of said electrons.

5. The combination within an evacuated envelope of an electron emitting cathode, an oscillatory electrode, means for causing electrons emitted from said cathode to follow spiral paths about an axis passing through said cathode, collecting electrodes, and means including a reticular accelerating electrode positioned in the path of said electrons for causing a portion of said electrons to impinge on said collecting electrodes.

6. The combination including an electron emitting cathode, a segmented cylindrical anode positioned about said cathode, means for causing electrons emitted from said cathode to follow spiral paths about said cathode, end plate electrodes positioned opposite the open ends of said anode and lying in planes perpendicular to said cathode for collecting electrons which impinge thereon, and electrode means for reducing the velocity of said impinging electrons.

7. An electron discharge device comprising a filamentary cathode, a segmented cylindrical anode disposed about said cathode, a pair of grid-like accelerating electrodes disposed, respectively, adjacent the opposite ends of said anode and lying in planes perpendicular to said cathode, and a pair of decelerating end plate electrodes adjacent respective accelerating electrodes and parallel thereto.

IRVING WOLFF.
